UNITED STATES PATENT OFFICE

JOHN REICHERT, OF RACINE, WISCONSIN

COW HOPPLE

Application filed May 24, 1928. Serial No. 280,294.

This invention has for its primary object the provision of a hopple for domestic quadrupeds, particularly cows, that will reduce to the minimum possibility of injury to the legs of the animal consequently that will be humane in use, simple, strong and durable in construction, easily operated, and powerful in action, and that will avoid the necessity of employing chain as the connecting and holding element; and those skilled in the art will readily perceive the foregoing and other objects in the light of the following explanation of the accompanying drawings showing what I now believe to be the preferred mechanical expression or embodiment of the invention from among other forms, constructions and arrangements within the spirit and scope of the invention.

The invention consists in certain novel features in construction and/or in combinations and arrangements as more fully and particularly set forth and specified hereinafter.

Referring to the accompanying drawings forming a part hereof,

Fig. 1 shows in perspective an example of a hopple of my invention applied to a domestic quadruped, such as a cow.

Fig. 2 shows the hopple of Fig. 1 in perspective, dotted lines indicating in part the hind legs of the animal, dotted lines also showing the form of the return bend or bight of the rope although in an abnormal position.

Fig. 3 is a detail perspective of the near leg hook of Figs. 1 and 2.

Fig. 4 is a detail perspective of the far leg hook, the return bend portion of the rope being shown.

Fig. 5 is a perspective of a modified form. The hopple comprises a pair of shackles, one for each hind leg, adapted to fit on the hamstring portions of the legs above the points of the hocks and project forwardly at the outer sides of the legs, and a strong flexible double-length connection of the rope

type at one end securely coupled to one (the right hand or near) shackle and adapted to extend transversely therefrom in front of the hind legs to the other (the far side or left hand) shackle and from thence back to the near side or original shackle with its free end adapted for quick attachable and detachable securing to said near side shackle; the central intermediate portion of the rope being confined to said far side shackle to form a bight or return bend having a longitudinally running or slipping fit with said far side shackle to permit longitudinal drawing or slipping of the rope with respect to said shackle to attain a powerful block and tackle leverage or action in drawing the two shackles and the hind legs toward each other by pull on the free end of the rope from the near side preparatory to fastening said free end of the rope to the near side shackle.

In the particular embodiment illustrated, each shackle is in the form of a hook composed of strong more or less wide band material, such as one length of band steel bent to the desired form. The hook is formed to fit forwardly over the hind leg above the hock point with the comparatively short flat bill 1, of the hook fitting the inner side of the leg and the comparatively long shank 2, of the hook fitting the outer side of the leg. The shank 2, of the right or near hook, is formed, near its forward end, with a rope hole or perforation 3, through which the double length strong rope 4, is threaded. This end of the rope is anchored and confined to said hook by a suitable stop head, such as permanent knot 4a, preventing the anchored end of the rope from pulling through the hole 3.

The intermediate portion of the flat wide shank 2, is longitudinally slit and punched outwardly to form a longitudinally inclined and rearwardly projecting tongue 5, free at its rear end, and this tongue cooperates with the outer side face of the shank 2, in form-

ing a rearwardly opening longitudinally-tapered locking and wedging slot or socket for the free end of the rope. This particular hook, of the pair, is termed the "near" or 5 "right hand" hook because it is applied to the hind leg adjacent to the location of the operator, and for milking purposes this is usually the right hand side of a cow. The other or far hook is preferably formed with a shank 10 having a forward extension 2a, that extends forwardly at the outer side of the far or left hand hind leg to which said far hook is applied. This extension 2a, also preferably is offset laterally or inwardly. This shank extension 2a, is so formed that the central portion of the rope 4, is confined or loosely coupled thereto in such manner as to form the 15 rope with a return bend or bight 4b, slideable through the shank and over the shank surfaces 2c engaged thereby, and hence permitting the rope to be pulled longitudinally through said extension 2a. This result can be attained by forming a pair of relatively large transverse holes 2c, through the extension that are 20 spaced apart a substantial distance longitudinally of the extension, and providing the extension with a transverse outwardly offset curved bulge or rounded corrugation 2d, between the holes 2c, to form a rounded rope 25 bight or return bend forming outer surface 2e, over which the rope transversely extends from one hole 2c, to the other hole, with a sliding fit. The rope and shackles (hooks) are assembled by threading the rope 4, inwardly 30 through rope hole 3, in the shank of the near hook so that the rope end stop, such as large knot 4a, will abut the outer side of the shank to prevent the rope end slipping through the hole. The free end of the rope is then 35 threaded outwardly through the rope hole 2c, most remote from the front free end of the shank-extension 2a, of the other or far hook. The rope is then bent or doubled back and its free end threaded inwardly through the outer 40 or other rope hole 2c, toward the near hook. The free end of the rope is then formed with a stop, such as hard knot 4c, to prevent accidental unthreading of the rope through holes 2c, and also to prevent the free end of the 45 rope accidentally slipping past the locking tongue 5, when secured thereby.

The two hooks are applied to the hind legs of the animal, with the hook shanks extended forwardly at the outer sides of the legs and 50 with the rope in front of the legs and extending transversely thereof connecting the shanks of the two hooks, with the free end of the rope hanging loosely from the extension of the far hook. The operator then from the 55 near hook side of the animal, pulls longitudinally on the free end of the rope in a direction toward the near side, thereby exerting a block and tackle action on the two hooks in drawing the animal's hind legs toward each other, 60 as the intermediate portion of the rope slips

longitudinally through the holes 2c, and across the intermediate rounded surface 2e, to exert pull on the near hook shank through the medium of the rope stop 4a, while the free end of the rope and the rope bend or bight also exert pull in the opposite direction on the far hook shank through the rounded portion 2e, thereof. When the rope has been tightened to the desired degree, the free end of the rope is passed transversely across the front edge or side of the near or right hind leg and secured to the near hook by wedging the same behind the locking tongue 5, and thereby securing the return ply of the rope to the near hook. The rope can be quickly and easily released, when the hopple is to be removed, by upward and rearward pull of its free end to release and free the same from the locking hook. As the rope 4, is smooth in so far as animal injuring projections are concerned, the hopple is exceedingly humane and avoids the cruel action of the chain lengths commonly employed, as well as difficulty encountered in handling chain lengths in securing and releasing hopples. I also avoid the use of swingable links as the connecting elements between the securing tie and the hooks, as these links are injurious to the animal's legs as well as otherwise objectionable in operation and use. 95

Either of the hooks of my hopple can be employed to secure the animal's tail, by grasping the tail between the hook bill and animal's leg.

Instead of providing the shank of the far hook with two rope holes and an intermediate rounded surface to provide the rope bight and the sliding contact of the rope with the hook shank in attaining the block and tackle connection, said shank can be slotted to receive a pulley 8, mounted on a suitable axis carried by ears 9, formed by bending the band steel of the hook shank at opposite sides of the slot, see Fig. 5. The rope bend or bight will thus fit the pulley and the opposite plies or lengths of the rope will pass to and from the pulley, through the slot in the hook shank. The action of the rope will be the same where the pulley 8, is employed as in the formation of Fig. 1. 115

What I claim is:—

1. A hopple including a near leg hook; a far leg hook having openings therein; and an elongated rope anchored at an end to the near hook and extending therefrom to and returning from the far hook, said rope extending through said openings in the far hook and thereby forming a return bend in said rope confined to said far hook with a running fit, whereby longitudinal pull on the free return length of the rope will draw the animal's legs on which the hooks are fitted toward each other with a block and tackle action, said near hook having means for 120

quick attachment and release of the return rope length free end.

2. A hopple including a near leg hook; a far leg hook, each embodying a hook bill having a shank; a doubled return-length 5 rope connecting the shanks of said hooks, the shank of said far leg hook being extended rearwardly and having the openings for the outward and return passage of said rope there-through with a running engagement, 10 said far hook shank having means to fit the return bend of said rope, one end of said rope being confined to the near hook shank; and means for attaching and detaching the 15 return length of the rope.

3. A hopple including leg shackles, and a connecting rope, the far leg shackle having a shank elongated rearwardly and deflected laterally and provided with openings, said 20 rope anchored at one end to the near leg shackle and extending therefrom to said far leg shackle and passing outwardly and inwardly through said openings, thereby forming a return bend or bight.

4. A hopple including leg shackles, each 25 having a shank; and a doubled return-bend rope directly connecting the shanks of said shackles, one end of said rope being anchored in one of said shanks, which shank is provided with a slot and a fixed free-end finger 30 elevated over said slot and from the adjacent side surface of said shank and cooperating with said slot and surface to wedge and lock the other end portion of said rope when 35 said rope is forced inwardly under and longitudinally of said finger and to release said rope when pulled outwardly longitudinally of said finger; the shank of the other shackle provided with means forming a bight or return bend in said rope whereby the rope is 40 coupled to said shank with a running fit.

5. A hopple including leg shackles having shanks; and a doubled return-bend rope the 45 ends of which are adapted to be secured to the shank of one shackle, the rope passing through the shank of the other shackle with a running fit and confined thereto at its bight or return-bend; one of said shanks provided with means for securing and releasing the 50 return length of said rope, the other end of said rope being anchored to said shank; the other shank being provided with means forming and fitting the return bend in the rope, and providing for longitudinal running of the rope through said shank.

6. A hopple including leg shackles; and a doubled return-bend rope connecting said shackles, said rope being anchored at one end to one of said shackles, which shackle is 60 provided with means for securing the other end of said rope; the other shackle having spaced openings for the free outward and return passage of said rope and an intervening rounded portion to fit the return bend of 65 said rope.

7. A hopple including leg shackles; and a doubled return bend rope directly connecting said shackles; one end of said rope being anchored to one of said shackles, which shackle provides means for the attachment 70 and release of the other end of said rope; the other shackle providing for the free longitudinal movement of the rope therethrough and being provided with a pulley wheel mounted therein and fitting in the return 75 bend in said rope.

Signed at Washington, District of Columbia, this 24th day of May, 1928.
